UNITED STATES PATENT OFFICE.

JOE M. ANGEL, OF PAULS VALLEY, OKLAHOMA.

HORSE COLLAR.

Application filed October 7, 1927. Serial No. 224,689.

This invention relates to improvements in horse collars and has for an object the provision of a collar in which the cover is formed of inner and outer sections which are continuous from the inner edge of the body to the outer edge of the rim of the collar, with the adjacent edges of the sections secured together, so that no seam is necessary in the hame recess where the greatest amount of wear occurs. A collar structure is thus provided which will more effectually resist wear in the hame of the recess and which may be more easily repaired than collars whose seams comprise more than two thicknesses of material. In addition, the invention provides a collar of simple and durable construction which may be cheaply made.

With the above and other objects in view, the invention further includes the following novel features and details of construction, to be hereinafter more fully described, illustrated in the accompanying drawings and pointed out in the appended claims.

In the drawings:

22. Figure 1 is a perspective view of a horse collar constructed in accordance with the invention.

Figure 2 is a fragmentary view on an enlarged scale.

30. Referring to the drawings in detail where-in like characters of reference denote corresponding parts, the reference character 10 indicates the padded body or draft portion of the collar while 11 indicates the padded neck or rim portion, both of which may be shaped in the ordinary manner.

Ordinarily, the cover of the collar has its adjacent edges secured together within the hame seat 13 and usually a separate piece of material extends around the body 10 and a separate piece around the rim 11 with the edges overlapping within the hame seat and secured together at this point. This provides four thicknesses of material through which the stitching or lacing must pass and as this portion of the collar is subject to the greatest wear, when the stitching or lacing breaks, and the cover separates at this point, it is a difficult and expensive operation to repair the collar. In some collars, the edges within the hame seat instead of overlapping are abutted in order to reduce the number of thicknesses of material at this point, but

this does not overcome the disadvantage of providing a seam within the hame seat where 55 the greatest wear occurs.

The present invention overcomes the above noted and other disadvantages by forming the cover of inner and outer sections 14 and 15. These sections are connected along 60 the outer edge of the body 10 by lacing or stitching 16 and along the outer edge of the rim 11 by lacing or stitching 17. The material of which the sections 14 are formed is thus continuous between the edges 16 and 17. Stitching or lacing 18 is provided around the hame seat 13 so that the cover between the body 10 and rim 11 is connected in a manner to provide only two thicknesses 65 of material at this point. If desired, the 70 collar may be stitched upon opposite sides of the lacing 18 as shown at 19 for convenience of inserting the lacing. Should the lacing wear and break away at this point, it 75 may be readily replaced.

The invention is susceptible of various changes in its form, proportions and minor details of construction and the right is herein reserved to make such changes as properly fall within the scope of the appended 80 claims.

Having described the invention what is claimed is:-

1. In a horse collar, a cover for the body and rim, said cover comprising an inner section and an outer section secured together at the outer edges of the rim and body of the collar, and providing continuous inner and outer sections, said sections being slit, and a lace passed through said slits for lacing the 85 sections together along the hame seat of the collar.

2. In a horse collar, a cover for the body and rim, said cover comprising an inner section and an outer section secured together 90 at the outer edges of the rim and body of the collar, and providing continuous inner and outer sections, said sections being slit, and a lace passed through said slits for lacing the sections together along the hame seat 95 of the collar, said sections being stitched together along the seat above and below said lace.

In testimony whereof I affix my signature.

JOE M. ANGEL.
